US00D811372S

(12) **United States Design Patent** (10) **Patent No.:** **US D811,372 S**
(45) **Date of Patent:** **** Feb. 27, 2018**

(54) **REMOTE CONTROL**

(71) Applicant: **Telefonaktiebolaget LM Ericsson (publ)**, Stockholm (SE)

(72) Inventors: **Ignazio Moresco**, San Francisco, CA (US); **Hugh Hitchens**, San Anselmo, CA (US); **Kah Loon Liew**, Campbell, CA (US); **Keith Okabe**, San Mateo, CA (US)

(73) Assignee: **TELEFONAKTIEBOLAGET LM ERICSSON (PUBL)**, Stockholm (SE)

(**) Term: **15 Years**

(21) Appl. No.: **29/586,754**

(22) Filed: **Dec. 6, 2016**

Related U.S. Application Data

(62) Division of application No. 29/532,522, filed on Jul. 7, 2015, now Pat. No. Des. 777,143.

(57) **CLAIM**

The ornamental design for a remote control, as shown and described.

DESCRIPTION

FIG. 1 shows a perspective view of our new design of a remote control;

FIG. 2 shows a front view of the remote control of FIG. 1; FIG. 3 shows a back view of the remote control of FIG. 1; FIG. 4 shows a top view of the remote control of FIG. 1; FIG. 5 shows a bottom view of the remote control of FIG. 1;

FIG. 6 shows a right view of the remote control of FIG. 1; and,

FIG. 7 shows a left view of the remote control of FIG. 1. The broken lines in the figures illustrate features of the remote control which form no part of the claimed design.

1 Claim, 4 Drawing Sheets
